UNITED STATES PATENT OFFICE.

NICHOLAS SIMON, OF NEENAH, WISCONSIN.

DESIGN FOR A CHEESE.

SPECIFICATION forming part of Design No. 34,520, dated May 14, 1901.

Application filed March 11, 1901. Serial No. 50,763. Term of patent 7 years.

To all whom it may concern:

Be it known that I, NICHOLAS SIMON, a citizen of the United States, residing at Neenah, in the county of Winnebago and State of Wisconsin, have invented and produced a new and original Design for a Cheese, of which the following is a specification, reference being had to the accompanying drawings, forming part thereof.

10 Figure 1 is a plan of the top side of the cheese. Fig. 2 is a plan of the bottom side of the cheese. Fig. 3 is a side elevation or edge view of the cheese. Fig. 4 is a vertical section of the cheese upon the line *a a* of Fig. 1.

15 As shown in the drawings, the leading feature of my design consists of a polygon having twelve equal sides and having twelve V-shaped radial grooves 1, which intersect the twelve outer angles of the polygon and divide

20 it into twelve equal acute-angular sections, said V-grooves being arranged opposite each

other upon opposite sides of the cheese. There is also a half-circle groove 2 around each of said acute-angular sections, near their outer edges, upon the top side of the cheese, which forms smaller acute-angular sections or name-plates for receiving any desired inscription. The outer edge of the cheese or the short side of each of the acute-angular sections is a straight and smooth surface. 25

Having thus described my said invention, what I claim as new, and desire to secure by Letters Patent, is—

30 The design for a cheese as herein shown and described.

35 In testimony whereof I have signed my name in the presence of two subscribing witnesses.

NICHOLAS SIMON.
